SNOW PLOW

Newton B. Frame and John W. Keim,
Buckhannon, W. Va.Substituted for application Serial No. 190,666,
February 15, 1938. This application September
28, 1945, Serial No. 619,025

1 Claim. (Cl. 37—42)

1

This invention relates to snow plows, and particularly to highway snow plows of the portable type designed to be mounted on the front ends of trucks, tractors or the like; this application being filed as a substitute for our abandoned application, Serial No. 190,666.

An important object of the invention is to provide a snow plow of this character especially constructed for use on light trucks or tractors, the construction of the plow mounting being such that the plow may be operated at a comparatively rapid rate of speed, without danger of damage to the plow or motor vehicle to which it is attached, should the plow strike a stationary obstruction in the highway or road surface.

Another important object of the invention is to provide a snow plow blade curved in such a way that the blade will have a scooping action causing the snow to take a swirling motion, with the result that the snow is thrown laterally and broadcasted evenly and not piled at the edge of the road as is common with snow plows now in use, and which push or shove the snow to one edge of the road.

A still further object of the invention is to provide means whereby the cutting edge of the blade will be protected against damage by contact with the highway surface, when the blade of the plow tilts on meeting an obstruction.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a perspective view illustrating a snow plow constructed in accordance with the invention as mounted at the front end of a truck.

Figure 2 is a plan view of the snow plow, the plow blade being shown in section.

Figure 3 is a vertical sectional view through the snow plow.

Figure 4 is a sectional view taken on line 4—4 of Figure 2.

Figure 5 is a fragmental plan view illustrating one end of the plow blade.

Figure 6 is a sectional view taken on line 6—6 of Figure 5.

Figure 7 is a perspective view illustrating the construction of the plow blade.

2

Figure 8 is an end elevational view of the plow blade, the position of the blade when tilting, being shown in dotted lines.

Figure 9 is a sectional view taken on line 9—9 of Figure 4.

Figure 10 is a fragmental sectional view through the blade, illustrating the adjustable stops for limiting the rearward movement of the blade.

Figure 11 is a sectional view taken on line 10—10 of Figure 10.

Figure 12 is a fragmental sectional view illustrating the pivotal connection between the supporting rods and plow of the device.

Figure 13 is a sectional view taken on line 15—15 of Figure 2.

Figure 14 is a detail view illustrating the pivotal connection between the supporting members of the plow and frame, which supports the plow.

Referring to the drawings in detail, the support for the snow plow includes an angle bar indicated by the reference character 5 to which the upstanding frame 6 is secured, as by welding. As shown, the bars of which the frame 6 is constructed, converge towards the upper end of the frame, where they are connected by means of the plate 7. Extending inwardly from the frame 6, at a point substantially intermediate the ends of the frame, are bars 8, which bars are of widths to fit within the open sides of the usual channel 30 bars providing the side rails of a truck. As shown, these bars are fitted within the open sides of the channel bars, and secured as by means of bolts 9, so that the frame may be readily and easily disconnected from the truck or vehicle supporting it.

The lower ends of the frame 6, extend appreciable distances below the bars 8, the lower ends of the frame being braced against rearward movement, by means of the bars 10 that are bolted 40 to the side rails of the truck, at the rear end of the bars, the forward ends of the bars being bolted to the angle bar 5, by the bolts 11.

Supported by the angle bar 5 and extending forwardly therefrom at points adjacent to the 45 ends of the angle bars, are sectional bearings 12, the removable sections 13 of the bearings being held in place by means of the bolts 14.

The sectional bearings 12 provide a support for the shaft 15 on which the tubular sections 16 50 of the pivoted supporting members 17 are mounted. Openings are formed in the ends of the shaft 15 for the reception of suitable cotter keys or bolts, whereby the shaft may be secured within its bearings, against displacement.

55 These pivoted supporting members 17 provide

the support for the blade of the snow plow, which is indicated by the reference character 18. The connection between the plow blade 18 and the pivoted supporting members 17, is made through the rods 19 that are welded within the pivoted supporting members 17, as clearly shown by Figure 12 of the drawings. The blade 18 of the snow plow, is braced throughout its length, by means of the channel bars 20 arranged in transverse spaced relation with respect to each other, the channel bars being curved to conform to the curvature of the blade, to support the blade against transverse bending, should the plow meet with an obstruction. Extending longitudinally of the blade 18 is an angle bar 21 that is welded to the channel bars 20, as shown by Figure 2 of the drawings. Extending rearwardly from the angle bar 21, at points adjacent to the ends thereof, are bearing plates 22 that are formed with aligning openings for the reception of the bolts 23. Positioned on the bolts 23 and arranged between the bearing plates 22, are sleeves 24 to which the straps 25 are welded, the free ends of the straps being spaced apart to accommodate the ends of the rods 19, said straps being formed with openings to accommodate the bolts 26 pivotally connecting the rod 19 with the straps. Thus it will be seen that due to this construction, the plow may be moved laterally on the bolts 26, and vertically on the bolts 23. Secured to the shaft 15, and rising therefrom at a point substantially intermediate the ends thereof, is a substantially short channel bar 27 which is formed with an opening to receive one end of the eye bolt 28 which is adjustably held to the channel bar 27, by means of the nuts 29. Connected with this eye bolt 28, is a link 29 that has pivotal connection with the tubular housing 30 in which the coiled spring 31 is held. One end of the tubular housing 30 is closed by means of the ring 32, which provides a stop for one end of the coiled spring 31 restricting movement of the coiled spring in one direction so that the spring 31 will be compressed, when pressure is brought to bear on the opposite end of the spring. Extending through the ring 32, and through the coiled spring 31, is a length of chain indicated by the reference character 33, the inner end of the chain being connected with the eye bolt 34 that extends through the disk 35 which is formed with an opening to receive the eye bolt, there being provided a nut 36 for securing the eye bolt to the disk. At the opposite end of the chain 33, is a link 37 having openings to receive the bolt 38 designed to secure the link and one end of the chain, to the curved rib 39 extending from the rear of the plow blade. A plurality of spaced openings indicated at 40 are provided in the rib 39 so that the link 37 may be adjusted longitudinally of the rib 39 to vary the tension of the spring 31, and adapting the plow for various road conditions.

The frame 6 provides a support for the cylinder 40 in which the piston rod 41 extends, the piston rod carrying the usual piston at its inner end. Secured to the outer end of the piston rod 41 is a pulley support 42 in which the pulley 43 operates. A pulley support indicated by the reference character 44 is secured at the upper end of the frame 6, and extends towards the plow blade of the machine. The pulley 45 operates in the pulley support 44. Operating over the pulleys 43 and 45 is a cable 46 that has one end thereof connected to the hook 47 that is hooked into the link 48 of the chain 49, that in turn is se-

cured to the rear of the plow blade 18. The opposite end of the cable 46 is secured to the cylinder 40, at 50. A pump handle indicated by the reference character 51 forms a part of a suitable pump mounted on one end of the cylinder 40, whereby air may be forced against the piston of the rod 41, to move the piston rod and pulley 43 supported thereby, away from the lower end of the cylinder. It is obvious that as the piston rod 41 moves outwardly, the cable is shortened, and the plow blade of the machine is elevated. In order to lower the plow blade, it is only necessary to release the air in the cylinder 40, whereupon the weight of the plow will return the piston rod 41 to its normal position.

The reference character 52 designates forwardly curved plates formed with cut-out portions in which the nuts 53 are welded. Operating in the nuts 53, are bolts 54 that are supplied with lock nuts 55, whereby the bolts 54 may be held in various positions of adjustment. The heads 56 of the bolts 54, provide stops against which the blade engages, restricting rearward movement of the blade, when it is returned to its normal operating position, by means of the coiled spring 31. By adjusting these bolts 54, it will be obvious that the normal operating position of the plow blade may be adjusted to meet various requirements.

In order that the cutting edge 57 of the plow blade will operate in spaced relation with the ground surface over which the plow is moving, supporting wheels 58 are secured to the rear of the plow blade, the supporting wheels being adjustable vertically within the supports 59, adjusting the normal operating position of the blade.

As clearly shown by the drawings, the curvature of the blade is such that the snow is scooped by the cutting edge 57 thereof, and the snow is given a swirling motion discharging the snow through one end of the blade. Thus the snow is broadcast at the side of the road, and is not piled up along the edge of the road as is usual with snow plows in common use. One end of the curved plow blade is closed by means of the plate 60, the plate being of a length to extend beyond the surface of the curved plow blade, providing a support for the blade, when the blade is tilted to a position as shown by Figure 1 of the drawings. The lower front corner of the plate 60 is cut away and curved so that the blade may pivot readily to return to its normal operating position, after it has passed over an obstruction to move the blade. From the foregoing it will be seen that due to the specific construction of the blade, and the means for supporting the blade, the snow plow may be mounted at the front end of a rapidly moving truck, with the result that the time required in removing snow from the usual highway, will be reduced to the minimum.

In the event that the plow should strike an obstruction such as a stone frozen in the road surface, the plow will tilt, from the position shown by Figure 3 of the drawings, to a position as shown by Figure 1, allowing the blade to move over the obstruction. Immediately upon passing over the obstruction, it is obvious that the blade will be returned to its normal operating position, by means of the coiled spring 31 which has been placed under tension by the forward movement of the upper end of the plow.

We claim:

In a snow plow, a support adapted to be mounted on the front end of a tractor, said support comprising a shaft, horizontal tubular mem-

bers mounted on the shaft, the adjacent inner ends of the tubular members being spaced apart, tubular supporting members extending forwardly from the outer ends of the horizontal tubular members, a channel bar secured to the shaft and disposed between the adjacent ends of the horizontal tubular members holding the horizontal tubular members in spaced relation with respect

to each other, a curved plow blade, rods extending into the free ends of the forwardly extended tubular members, means for mounting the plow blade for vertical pivotal movement on the forward ends of the rods, and means for yieldingly holding the plow blade in its operative position.
